UNITED STATES PATENT OFFICE

GUSTAVE E. VILLARET, OF LEONIA, NEW JERSEY, ASSIGNOR TO LIGHTING APPLIANCE COMPANY, INC., OF NEW YORK, N. Y.

DESIGN FOR A LIGHTING FIXTURE MEMBER OR ARTICLE OF SIMILAR NATURE

Application filed April 1, 1931. Serial No. 39,324. Term of patent 3½ years.

To all whom it may concern:

Be it known that I, GUSTAVE E. VILLARET, a citizen of the United States, residing in Leonia, in the county of Bergen and State of New Jersey, have invented a new, original, and ornamental Design for a Lighting Fixture Member or Article of Similar Nature, of which the following is a specification, reference being had to the accompanying drawings, forming a part thereof.

Fig. 1 is a perspective view of a lighting fixture member showing my new design.

Fig. 2 is a bottom plan view thereof. The portions shown in broken outline are mere repeats of those shown in full outline.

I claim:

The ornamental design for a lighting fixture member or article of similar nature, as shown and described.

In testimony whereof I affix my signature

GUSTAVE E. VILLARET
